HELICALLY WOUND BRUSH AND HOLDER
THEREFOREdward Losiewicz and George Brocklehurst,
Detroit, Mich.

Application January 30, 1948, Serial No. 5,396

10 Claims. (Cl. 15—182)

1

The invention relates generally to a brush comprising a helically wound longitudinal brush element. The brush element preferably consists of a longitudinal metallic channel strip having bristles extending transversely therefrom and held in place by a longitudinal core member within the channel of the strip. The brush element, as described, is helically wound to form a brush with the bristles extending in generally radial directions. The invention relates more specifically to a rotatable holder for such a helically wound brush and to the combination of the brush with the holder.

One object of the invention is to provide a holder for a helically wound brush such as described, which holder comprises a rotatable arbor and a member movable relatively to the arbor to forcibly engage the interior of the brush so as to tend to expand it and thus firmly hold it in place.

Another object of the invention is to provide a rotatable holder such as last above set forth, wherein the relatively movable member is provided with grooves for receiving some of the convolutions of the helically wound channel strip of the brush, so as to prevent endwise movement of the brush with respect to the arbor.

Another object of the invention is to provide a combination of a helically wound brush and a holder having the above described characteristics.

Other objects of the invention will be apparent from the drawing and from the following specification and claims.

In the drawing we have shown in detail a preferred embodiment of the invention, but it will be understood that various changes may be made from the construction shown, and that the drawing is not to be construed as defining or limiting the scope of the invention, the claims forming a part of this specification being relied upon for that purpose.

Of the drawing,

Fig. 1 is a side view of a brush and holder embodying the invention.

Fig. 2 is a vertical sectional view.

Fig. 3 is a left end view.

Fig. 4 is a vertical sectional view similar to Fig. 2, but omitting the brush and showing the relatively movable member of the holder in a different position.

Fig. 5 is a plan view of the holder.

Referring to the drawing, 10 represents the brush in its entirety. The brush 10 comprises a helically wound longitudinal brush element which preferably includes a longitudinal channel 12

2

rolled from a longitudinal metallic strip. A longitudinal core member 14 such as a wire is positioned within the channel of the channel strip and bristles 16 constituting a longitudinal layer are folded around the core member within the channel, the end portions of the bristles projecting transversely from the channel through the neck between the front portions of the side walls thereof. During manufacture the bristles 16, while straight, are deposited with the core member 14 on the channel strip before the sides thereof are closed to their final positions. The core member is guided into the channel, thus folding the bristles around it. The sides of the channel strip are then rolled or pressed against the bristles to bind the several strips together by pressure.

The brush element as described is ordinarily initially straight, and it is then helically wound on a suitable mandrel into the form shown in the drawing to provide longitudinally spaced convolutions. While the invention is not necessarily so limited, the brush is preferably so wound that the convolutions near one end are of successively smaller diameters to provide a taper. At one end of the brush, which will be referred to as the free end and which is ordinarily the smaller end, the brush element is extended and bent for engagement with a driving lug on the arbor with which the brush is to be used. As shown, the extension comprises a loop having two opposite parallel portions 18 and 20 which are equally spaced from the brush axis. If desired, the extreme end portion of the brush element at the opposite end of the brush may be connected with the next adjacent convolution by spot welding or otherwise. This end portion of the brush element is indicated at 22 in Fig. 1. After the brush has been formed as described, the ends of the bristles may be trimmed to provide any desired contour.

40 The holder for use with a brush such as 10 comprises an arbor 24 which is adapted to be supported at least at one end, and it is shown in the drawing as adapted to be supported at one end only, that is, at the right end. Ordinarily the arbor 24 is rotatable, but the invention is not necessarily so limited. As shown, the arbor has a central hole 26 for receiving the end portion of a rotatable spindle 28, the arbor being connected with the spindle by any suitable means such as a socketed set screw 30. The arbor 24 has a circumferentially extending exterior area adapted for engagement with the interior of the brush. When the brush is tapered as shown, the arbor is similarly tapered.

55 When the brush is provided with an extension

by which it may be driven, the arbor is provided at its free end with a lug adapted for engaging the extension. As shown, the extension on the brush comprises two parallel portions 18 and 20 at one end of the brush element, and the arbor 24 has an integral lug 32 with flat sides which are adapted to fit between the said portions 18 and 20.

The arbor 24 is provided with a lateral opening in the brush engaging area thereof and a movable brush tightening member is located chiefly within the said lateral opening. Means is provided for moving the tightening member within the opening so as to force the outer face thereof against the inner portions of some of the convolutions of the channel strip of the brush. The shape of the lateral opening in the arbor and the shape of the relatively movable brush tightening member may be widely varied, but preferably the said opening in the arbor is a longitudinal slot 34. When the said opening is a slot such as 34, the movable brush tightening member is a longitudinal bar 36 fitting the slot and extending lengthwise thereof. With a tapered arbor the bar is correspondingly tapered.

The bar 36 is movable outward relatively to the arbor and preferably it is so movable about a transverse axis adjacent the free end of the arbor. As shown, a transverse pivot pin 38 extends through the bar 36 and through the adjacent portion of the arbor. Means is provided for moving the bar pivotally outward and this means preferably comprises a socketed screw 40 extending radially through a threaded radial hole in the bar 36. The inner end of the screw 40 engages with the arbor. In order that the screw 40 may be accessible with the brush in place on the holder, the bar 36 extends beyond the brush and the screw 40 is located in the extending portion of the bar. In order that the screw 40 may be of suitable size, the bar is preferably enlarged to provide a boss 42 and the arbor is provided with an opening 44 communicating with the slot 34 and of suitable size to receive the boss 42.

Preferably, a portion of the outer face of the bar is provided with transverse grooves 46 which are shaped and longitudinally spaced to receive some of the convolutions of the channel strip of the brush 10. The grooves 46 are preferably formed only in that portion of the outer face of the bar which is spaced from the pivot and which therefore has a substantial amount of movement. The portion of the outer face of the bar which is adjacent the pivot is preferably smooth.

When the brush 10 is to be mounted on the holder, the screw 40 is partly withdrawn so as to permit the bar 36 to occupy the relative position shown in Fig. 4. Then the brush 10 is pushed into place with the lug 32 on the arbor entered between the portions 18 and 20 on the brush extension. Then the screw 40 is turned to force the bar 36 pivotally outward from the position shown in Fig. 4 to the position shown in Fig. 2. The grooves 46 receive and fit some of the convolutions of the channel strip of the brush, and the outer face of the bar in moving outward tends to expand the brush so as to firmly hold it in place. The engagement of the inner portions of the brush convolutions with the grooves 46 prevents any endwise movement of the brush with respect to the holder.

When the brush is to be removed, the screw 40 is partly withdrawn so as to permit the bar 36 to move from the position shown in Fig. 2 to the position shown in Fig. 4. Then the brush can be readily withdrawn from the holder.

What we claim is:

1. A holder for use with a brush comprising a metallic channel strip with bristles extending therefrom which strip is helically wound with the bristles extending outward and has longitudinally spaced convolutions, the said holder comprising in combination, a longitudinal arbor having a circumferentially extending exterior area adapted for engagement with the interior of the brush, the said arbor being provided with a lateral opening in the said brush engaging area thereof, a movable brush tightening member located chiefly within the said lateral opening and held to prevent relative longitudinal movement, the said member having transverse grooves in its outer face which grooves are shaped and longitudinally spaced for receiving and fitting the inner portions of some of the convolutions of the channel strip of the brush, and means for moving the tightening member in the outward direction in the said opening to force the grooved outer face thereof against the said inner portions of the last said convolutions.

2. A holder for use with a brush comprising a metallic channel strip with bristles extending therefrom which strip is helically wound with the bristles extending outward and which brush is tapered and has longitudinally spaced convolutions, the said holder comprising in combination a longitudinal arbor adapted to be rotatably supported at one end and having a circumferentially extending exterior area adjacent its free end adapted for engagement with the interior of the brush, the said arbor being tapered in conformity with the taper of the brush to provide a smaller diameter at its free end and the said arbor being provided with a longitudinal slot in the said brush engaging area thereof, a movable longitudinal bar located chiefly within the said slot and tapered in conformity with the taper of the arbor which bar is held to prevent relative longitudinal movement and has transverse grooves in its outer face, the said grooves being shaped and longitudinally spaced for receiving and fitting the inner portions of some of the convolutions of the channel strip of the brush, and means for moving the bar in the outward direction in the said slot to force the outer face thereof against the inner portions of some of the last said convolutions.

3. A holder for use with a brush comprising a metallic channel strip with bristles extending therefrom which strip is helically wound with the bristles extending outward and has longitudinally spaced convolutions, the said holder comprising in combination, a longitudinal arbor adapted to be rotatably supported and having a circumferentially extending exterior area adapted for engagement with the interior of the brush, the said arbor being provided with a longitudinal slot in the said brush engaging area thereof, a longitudinal bar located chiefly within the said slot and pivotally movable about a transverse axis near the free end of the arbor and in fixed relation thereto which bar has transverse grooves in its outer face, the said grooves being shaped and longitudinally spaced for receiving and fitting the inner portions of some of the convolutions of the channel strip of the brush, and means adjacent the end of the bar opposite the pivotal axis and beyond the said transverse grooves for moving the bar pivotally outward in the said slot to force the outer face thereof against the inner portions of some of the last said convolutions.

4. A holder for use with a brush comprising a metallic channel strip with bristles extending therefrom which strip is helically wound with the bristles extending outward and has longitudinally spaced convolutions, the said holder comprising in combination, a longitudinal arbor adapted to be rotatably supported and having a circumferentially extending exterior area adapted for engagement with the interior of the brush, the said arbor being provided with a longitudinal slot in the said brush engaging area thereof, a longitudinal bar located chiefly within the said slot and pivotally movable about a transverse axis near the free end of the arbor and in fixed relation thereto, the portion of the outer face of the bar adjacent the said transverse pivotal axis being smooth and the portion of the outer face of the bar spaced from the said axis having transverse grooves therein which grooves are shaped and longitudinally spaced for receiving and fitting some of the convolutions of the channel strip of the brush, and means for moving the bar pivotally outward in the said slot to force the said smooth and outer portions of the face thereof against the inner portions of the last convolution of the channel strip of the brush.

5. A holder for use with a brush comprising a metallic channel strip with bristles extending therefrom which strip is helically wound with the bristles extending outward and has longitudinally spaced convolutions, the said holder comprising in combination, a longitudinal arbor adapted to be rotatably supported and having a circumferentially extending exterior area adapted for engagement with the interior of the brush, the said arbor being provided with a longitudinal slot in the said brush engaging area thereof, a longitudinal bar located chiefly within the said slot and pivotally movable about a transverse axis near the free end of the arbor, and a radial screw engaging the bar and the arbor at a position remote from the said transverse axis for moving the former pivotally outward in the said slot to force the outer face thereof against the inner portions of some of the convolutions of the channel strip of the brush.

6. A holder for use with a brush comprising a metallic channel strip with bristles extending therefrom which strip is helically wound with the bristles extending outward and has longitudinally spaced convolutions, the said holder comprising in combination, a longitudinal arbor adapted to be rotatably supported and having a circumferentially extending exterior area adapted for engagement with the interior of the brush, the said arbor being provided with a longitudinal slot in the said brush engaging area thereof and being provided with an opening communicating with the slot at the end thereof opposite the free end of the arbor, a longitudinal bar located chiefly within the said slot and pivotally movable about a transverse axis near the free end of the arbor, the said bar having a boss at the end thereof opposite the pivot which boss is within the said opening in the arbor and has a threaded radial hole, and a radial screw in the threaded hole in the boss engageable at its inner end with the arbor for moving the bar pivotally outward in the said slot to force the outer face thereof against the inner portions of some of the convolutions of the channel strip of the brush.

7. The combination of a brush comprising a metallic channel strip with bristles extending therefrom which strip is helically wound with the bristles extending outward and has longitudi-

nally spaced convolutions, a longitudinal arbor having a circumferentially extending exterior area engaging the interior of the brush, the said arbor being provided with a lateral opening in the said brush engaging area thereof, a movable brush tightening member located chiefly within the said lateral opening and having transverse grooves in its outer face which grooves are shaped and longitudinally spaced for receiving and fitting the inner portions of some of the convolutions of the channel strip of the brush, and means accessible beyond one end of the brush for moving the tightening member in the outward direction in the said opening so that the grooved outer face thereof is in forced engagement with the inner portions of the last said convolutions.

8. The combination of a helically wound brush comprising a metallic channel strip with bristles extending outward therefrom, an arbor adapted to be rotatably supported and having a circumferentially extending exterior area engaging the interior of the brush, the said arbor being provided with a longitudinal slot in the said brush engaging area thereof, a movable longitudinal bar located chiefly within the said slot and pivotally movable about a transverse axis near the free end of the arbor, the said bar having transverse grooves in its outer face to receive some of the convolutions of the channel strip of the brush, and means accessible beyond the end of the brush opposite the said pivotal axis for moving the bar pivotally outward in the said slot so that the outer face thereof is in forced engagement with the inner portions of some of the convolutions of the channel strip of the brush.

9. The combination of a helically wound brush comprising a metallic channel strip with bristles extending outward therefrom, an arbor adapted to be rotatably supported and having a circumferentially extending exterior area engaging the interior of the brush, the said arbor being provided with a longitudinal slot in the said brush engaging area thereof, a movable longitudinal bar located chiefly within the said slot and pivotally movable about a transverse axis near the free end of the arbor, the said bar extending beyond the brush at the end opposite the said pivotal axis and provided adjacent the last said end with a radial threaded hole, and a radial screw in the said threaded hole engageable at its inner end with the arbor for moving the bar pivotally outward in the said slot so that the outer face thereof is in forced engagement with the inner portions of some of the convolutions of the channel strip of the brush.

10. The combination of a helically wound brush comprising a metallic channel strip with bristles extending outward therefrom, an arbor adapted to be rotatably supported and having a circumferentially extending exterior area engaging the interior of the brush, the said arbor being provided with a longitudinal slot in the said brush engaging area thereof, a movable longitudinal bar located chiefly within the said slot and pivotally movable about a transverse axis near the free end of the arbor, the portion of the outer face of the bar adjacent the said transverse pivotal axis being smooth and the portion of the outer face of the bar spaced from the said axis having transverse grooves therein longitudinally spaced to receive some of the convolutions of the channel strip of the brush, and means accessible beyond the end of the brush opposite the said pivotal axis for moving the bar

pivotedly outward in the said slot so that the outer face thereof is in forced engagement with the inner portions of the convolutions of the channel strip of the brush.

EDWARD LOSIEWICZ.
